ABSTRACT: A tobacco smoke filter is disclosed which is designed to remove some of the harmful and irritating sub-

stances from tobacco smoke, the filter comprising a filter-forming material or support which contains ester ether compounds of saccharides. Included are aldohexose and ketohexoses having polyalkylene glycol residues and disaccharides containing said hexoses. The compounds effective for the desired purposes may be represented by the following formulas:

wherein $\text{R}_1, \text{I}/\text{NR}_8$ represent any one of a polyalkylene group, a fatty acid ester group and hydrogen, at least one of the groups being a polyalkylene group and at least one of the groups also being a fatty acid ester group. The saccharide or saccharide derivative constitutes from 0.01 to 30 percent by weight of the filter.

TOBACCO SMOKE FILTER

This invention relates to tobacco smoke filters made of filter forming material containing specific ester ether compounds of saccharides. Tobacco smoke filter of the present invention can remove harmful and irritating substances to human body present in tobacco smoke, thereby making the harsh flavor of tobacco smoke milder to give to smokers satisfactory flavor. The term "filter-forming material" as employed herein, covers fiber, paper, sponge, felt, granule and powder, from which tobacco smoke filter is produced.

For the production of tobacco smoke filters capable of removing harmful and irritating substances contained in tobacco smoke, there have been used, in general, cellulose, cellulose acetate, starch, starch derivatives, silica gel, activated carbon and polyethylene glycol. These filters, however, are not satisfactory in that they cannot remove harmful substances without decreasing the flavor of tobacco smoke.

It has now been found that the harmful and irritating substances can be removed without decreasing the flavor by using filter-forming material containing specific ester ether compounds of saccharides.

The ester ether compounds of saccharides of the present invention are those of hexoses such as aldohexoses and ketohexoses having polyalkylene glycol residues and those of disaccharides containing said hexoses. When classified into pyranose-type and furanose-type compounds, the above-mentioned ester ether compounds may be represented, respectively, by the general formulas shown below.

In the above general formulas (I), (II), (III) and (IV), R_1 , R_2 , R_3 , R_4 , R_5 , R_6 , R_7 and R_8 represent one member selected from the group consisting a monovalent organic residue and hydrogen atom, one of said organic residue being a polyalkylene glycol ether group of the formula $-\text{alkylene}-(\text{O}-\text{alkylene})_n-\text{OH}$, e.g. a polyethylene glycol ether group of the formula $-\text{C}_2\text{H}_4-(\text{OC}_2\text{H}_4)_n-\text{OH}$; at least one of the remaining said organic residue being an acyl group of the formula $\text{RCO}-$, e.g. an acyl group having two to 19 carbon atoms.

This is, the present invention is concerned with a tobacco smoke filter made of filter-forming material containing at least one of the compounds represented by the general formulas (I), (II), (III) and (IV).

Each of the above-mentioned compounds has nonionic surface activity and is excellent in ability of absorbing such ir-

itating components contained in tobacco smoke as phenols. When a tobacco smoke filter made of filter-forming material containing such compounds is used, undesirable components present in tobacco smoke, e.g. phenols, can be removed without decreasing the flavor of tobacco smoke.

The aldohexoses belonging to group (I) include glucose, galactose, mannose, etc., the ketohexoses belonging to group (II) include fructose, sorbose, etc., the disaccharides belonging to group (III) include sucrose, etc., and the disaccharides belonging to group (IV) include lactose, cellobiose, maltose, etc.

The acyl groups to be added to said saccharides include fatty acid ester groups of fatty acids having two to 19 carbon atoms, such as acetyl, propionyl, stearyl, palmityl, oleyl, lauryl and myristyl groups. The number of carbon atoms of said fatty acids is preferably within the above-mentioned range from the point of ability of the resulting compounds for removing undesirable components present in tobacco smoke and melting point and viscosity of the resulting compound.

Further, the polyalkylene glycol residues to be added to the aforesaid saccharides include polyethylene glycol, polypropylene glycol, polyethyleneglycol and polybutylene glycol residues. The chain length of said polyalkylene glycol residue greatly affects the resulting compounds in surface active characteristics, viscosity, and melting point. And the chain length of the polyalkylene glycol residue is preferably in such a range that 1 to 50 moles, more preferably 5 to 20 moles, of alkylene glycol monomer has been condensed, from the point of ability for removing the harmful and irritating components, processability of the filter-forming material and the dimensional stability of tobacco smoke filters to be obtained.

Thus, the compounds to be contained into the filter forming material in accordance with the present invention are, for example, as follows:

The compounds belonging to group (I) are glucose acetate polyethylene glycol ether, galactose acetate polyethylene glycol ether, mannose acetate polyethylene glycol ether, etc., the compounds belonging to group (II) are fructose stearate polyethylene glycol ether, sorbitose stearate polyethylene glycol ether, etc.; the compounds belonging to group (III) are sucrose palmitate polypropylene glycol ether; and the compounds belonging to group (IV) are lactose palmitate polypropylene glycol ether, etc.

In accordance with the present invention, filter-forming material containing one or two or more of the compounds belonging to the above-mentioned group is shaped into tobacco smoke filters.

The filter-forming material employed for preparing the tobacco smoke filter in the present invention includes viscose rayon, cellulose acetate, polyamide, polyolefin or polyester fiber, paper and polyvinyl alcohol, cellulose acetate, polystyrene sponge. The fiber has preferably a single fiber denier of 1 to 10 and a total denier of 20,000 to 100,000. The fibers may be crimped. The filter-forming material may also be granules or felt.

The above-mentioned compound is added to the filter-forming material by the following manner:

In case of the filter-forming material is fiber, a solution or dispersion containing the compound is added to the fiber as an oil agent at extrusion step. Alternatively, a solution or dispersion containing the compound may be sprayed to the fibers in a plug machine where the fibers are rolled up to a rod-shaped filter plug. In this case, plasticizers and adhesives may be simultaneously added to the fibers.

In case the filter forming material is in other form than fiber, the compound is mixed with, penetrated into, or adhered onto the surface of, said filter-forming material. In spraying a dispersion containing the compound onto the filter forming material, it is markedly effective for the uniform adhesion of the compound onto the filter-forming material to use other surface active agent such as sucrose ester, polyalkylene glycol or the like as stabilizer of dispersion.

In any of the above-mentioned cases, the content of the present compound in the filter-forming material is 0.01 to 30 percent, preferably 0.05 to 20 percent by weight. If the content is less than 0.01 percent, the effect of the present invention is difficultly displayed, while if the content is higher than 30 percent, the filter to be obtained is not satisfactory in such dimensional stability required for tobacco smoke filter as hardness and in pressure drop characteristics.

In the present invention, substances capable of enhancing the filter characteristics, such as plasticizers, adhesives, and flavors, etc. may be simultaneously added with the present compound to the filter forming material.

The present invention is illustrated below with reference to examples.

EXAMPLE 1

An acetate fiber tow having 18 crimps per 25 mm., a single fiber denier of 4 and a total denier of 55,000 was thoroughly opened. Thereafter, a 10 percent aqueous emulsion of sucrose monopalmitate polyethylene glycol ether (condensate containing 10 moles of ethylene glycol) was uniformly added to the tow by use of a centrifugal spraying means so that the amount of said sucrose monopalmitate polyethylene glycol ether became 1 percent based on the weight of the tow. Subsequently, the tow was rolled up with paper, using a filter-plug-making machine, to a rod of 7.9 mm. in diameter and was then cut to a filter plug of 102 mm. in length. The thus-shaped filter plug was cut to filter tips of 17 mm. in length. These filter tips were individually attached by scotch tape to one end of 30 cigarettes to prepare samples for measuring the pressure drop and the amount of phenols in tobacco smoke and for organoleptic test.

On the other hand, a control filter was prepared under the same conditions as above, except that the 10 percent aqueous emulsion of sucrose monopalmitate polyethylene glycol ether was not added.

The filter of the present example and the control filter were compared in pressure drop and in amount of phenols in tobacco smoke passed through the filter to obtain the results as set forth in table 1.

The tobacco smoke filter of the present example was excellent in ability of removing phenols in tobacco smoke and, according to organoleptic test, flavor of tobacco smoke passed through the filter of the present example was rich taste and good mildness.

TABLE 1

Kind of filter	Pressure drop (mm. H ₂ O)	Phenols in smoke (mg./cigarette)
Control filter.....	46	0.046
Filter of Example 1.....	45	0.041

The pressure drop and the amount of phenols in tobacco smoke were measured according to the methods set forth below.

Method for measuring the pressure drop:

Instrument:

Constant air flow rate type pressure drop tester.

Condition:

Flow amount 20 ml./sec.

Method for measuring the amount of phenols in tobacco smoke:

Smoking conditions:

Instrument:

Automatic smoking machine:

Smoking interval:

Smoking time:

Amount of flow:

Length of stub:

30 seconds

2 seconds

17.5 ml./sec.

30 mm.

Number of cigarettes: 50

Phenols were quantitatively analyzed according to gas-chromatography.

5 Phenols contained in the tobacco smoke passed through the filter were collected by use of an alkaline liquid, separated and purified, and then extracted with ether to prepare a sample for gas-chromatography. Conditions for analyzing the amount of phenols according to gas-chromatography:

Column:	
Diocetyl sebacate	10%
Phosphoric acid	2%
"Diasolid-S"	3 m., 60-80 mesh
(Diatomaceous earth)	

Temperature:	
Thermostat	130° C.
Inlet	200° C.
Detector	100° C.

Detector: Hydrogen flame ion.

Carrier gas:	
N ₂	10 ml./4.2 sec.
H ₂	10 ml./13.5 sec.
Air	10 ml./1.4 sec.

Organoleptic test method:

20 The flavor of tobacco smoke was tested by 20 panel members with respect to the 4 items of aroma, taste, odor, mildness, and there were described items in which significant differences had been recognized.

Example 2

In the same manner as in example 1, except that the aqueous emulsion containing organoleptic 10 percent of sucrose monostearate polyethylene glycol ether (condensate containing 10 moles of polyethylene glycol) and 3 percent of sucrose dipalmitate was employed.

On the other hand, a control filter was prepared under the same conditions as above, except that the aqueous emulsion containing 10 percent of sucrose monostearate polyethylene glycol ether and 3 percent of sucrose palmitate was not added.

25 The filter of the present example and the control filter were compared in pressure drop and in amount of phenols in tobacco smoke passed through the filters to obtain the results as set forth in table 2.

40 The tobacco smoke filter of the present example was excellent in ability of removing phenols in tobacco smoke and, according to organoleptic test, the flavor of tobacco smoke passed through the filter of the present example was extremely rich in taste and good mildness.

TABLE 2

Kind of filter	Pressure drop (mm. H ₂ O)	Phenols in smoke (mg./cigarette)
Control filter.....	46	0.046
Filter of Example 2.....	46	0.040

EXAMPLE 3

After spinning, an acetate fiber tow having a single fiber denier of 4 and a total denier of 55,000 was treated with an emulsion oil agent comprising 12 parts of mineral oil, 8 parts of sucrose dipalmitate polypropylene glycol ether (condensate containing 8 moles of propylene glycol) and 80 parts of water, so that 2 percent based on the weight of the tow of the emulsion oil agent was adhered to the tow. After treatment with the emulsion oil agent, the tow was subjected to crimping to develop 18 crimps per 25 mm. and was then dried.

70 This acetate fiber tow was thoroughly opened, was contained 6 percent on the weight of the tow of triacetin as a plasticizer, was rolled up with paper, using a filter-plug-making machine, to a rod of 7.9 mm. in diameter and was then cut

to a filter plug of 102 mm. in length. The thus-shaped filter plug was cut to filter tips of 17 mm. in length. Subsequently, the filter tips were individually attached by Scotch tape to one end of cigarettes to prepare samples for measuring the amount of phenols in tobacco smoke and for organoleptic test.

On the other hand, a control filter was prepared under the same conditions as above, except that a commercially available oil agent for acetate fiber tow was used in place of the emulsion oil agent.

The filter of the present example and the control filter were compared in pressure drop and in amount of phenols in tobacco smoke passed through the filters to obtain the results as set forth in table 3.

The tobacco smoke filter of the present example was excellent in ability of removing phenols in tobacco smoke and, according to organoleptic test, the flavor of tobacco smoke passed through the present filters was extremely in rich taste and good mildness.

TABLE 3

Kind of filter	Pressure drop (mm. H ₂ O)	Phenols in smoke (mg./cigarette)
Control filter.....	48	0.086
Filter of Example 3.....	48	0.082

EXAMPLE 4

A mechanically crimped polypropylene fiber tow having a single fiber denier of 9.5 and a total denier of 60,000 was thoroughly untwisted. Thereafter, a 10 percent aqueous emulsion of glucose diacetate polyethylene glycol ether (condensate containing 10 moles of ethylene glycol) was uniformly added to the tow so that 1 percent based on the weight of the tow of the glucose diacetate polyethylene glycol ether was added to the tow. Subsequently, the tow was rolled up with paper, using a filter-plug-making machine, to a rod of 7.9 mm. in diameter and was then cut to a filter plug of 102 mm. in length. The thus shaped filter plug was cut to filter tips of 17 mm. in length. These filter tips were individually attached by Scotch tape to one end of cigarettes to prepare samples for measuring the amount of phenols in tobacco smoke and for organoleptic test.

On the other hand, a control filter was prepared under the same conditions as above, except that the 10 percent aqueous emulsion of glucose diacetate polyethylene glycol ether was not added.

The filter of the present example and the control filter were compared in pressure drop and in amount of phenols in tobacco smoke passed through the filters to obtain the results as set forth in table 4.

The tobacco smoke filter of the present example was excellent in ability of removing phenols in tobacco smoke and, according to organoleptic test, the flavor of tobacco smoke passed through the filter of the present example was in rich taste and good mildness.

TABLE 4

Kind of filter	Pressure drop (mm. H ₂ O)	Phenols in smoke (mg./cigarette)
Control filter.....	44	0.070
Filter of Example 4.....	42	0.052

EXAMPLE 5

A cellulose powder of about 0.8 mm. in grain size was immersed in an aqueous emulsion containing a mixture of 5 percent of glucose diacetate polyethylene glycol ether (condensate containing 10 moles of ethylene glycol) and 5 percent of fructose monooleate polyethylene glycol ether (condensate containing 5 moles of ethylene glycol), so that 4 percent based on the dry weight of the powder of the mixture of ester ether 5 compounds of saccharides was adhered to the powder. After drying, 0.4 g. of the thus-treated cellulose powder was packed into a plastic cell of 9 mm. in diameter and 35 mm. in length, and the cell was inserted in a cigarette pipe to prepare a sample.

10 15 On the other hand, a control was prepared in the same manner as above, except that the cellulose powder was not immersed in the aqueous containing the mixture of ester ether compounds of saccharides.

The filter of the present example and the control filter were 20 compared in pressure drop and in amount of phenols in tobacco smoke passed through the filters to obtain the results as set forth in table 5.

The filter of the present example was excellent in ability of removing phenols in tobacco smoke and was in rich taste and good mildness.

The methods for measuring the pressure drop and the amount of phenols in tobacco smoke, and the organoleptic test in the present example were effected by smoking four cigarettes with one cell.

TABLE 5

Kind of filter	Pressure drop (mm. H ₂ O)	Phenols in smoke (mg./cigarette)
Control filter.....	80	0.062
Filter of Example 5.....	82	0.037

EXAMPLE 6

Example 1 was repeated except that viscose rayon staples having 10 crimps per 25 mm., a single fiber denier of 4, apparent silver denier of 50,000 and cut length of 51 mm. were employed.

45 On the other hand, a control filter was prepared in the same manner as the present example except that the 10 percent aqueous emulsion of sucrose monopalmitate polyethylene 50 glycol ether was not added.

The filter of the present example and the control filter were compared in pressure drop and in amount of phenols in tobacco smoke passed through the filter to obtain the results as set forth in table 6.

TABLE 6

Kind of filter	Pressure drop (mm. H ₂ O)	Phenols in smoke (mg./cigarette)
Control filter.....	45	0.055
Filter of Example 6.....	43	0.052

65 According to organoleptic test, the flavor of tobacco smoke passed through the filter of the present example was rather harsh taste.

EXAMPLE 7

70 Spongeous plugs having at least 40 percent transverse cross section of the cylindrical mass interconnected cavities were made from polyvinyl acetate, polystrene, cellulose acetate and polyvinyl alcohol.

Those spongeous plugs were shaped in diameter of 7.9 mm. and length of 17 mm. tips.

The tips were divided into two groups and the one of the groups was dipped into a 10 percent aqueous emulsion of sucrose monoacetate polyethylene glycol ether (condensate containing 10 moles of ethylene glycol). Weight increase of the tips after drying was 1 percent based on the weight of the tips. Each tip was attached by Scotch tape to one end of cigarette.

The pressure drop and the amount of phenols in tobacco smoke were measured to obtain the results shown in table 7.

TABLE 7

Kind of filter (sponge)	Dipping	Pressure drop (mm. H ₂ O)	Phenols in smoke (mg./cigarette)

EXAMPLE 8

Cellulose paper of 10 g./m.² was uniformly sprayed with an aqueous emulsion containing 10 percent of sucrose monopalmitate polyethylene glycol ether. Weight increase of the paper was 1 percent. The paper was cut into 102 mm. length and 25 mm. width, and five sheets of the cut papers were piled and rolled up to make a filter plug of 7.9 mm. in length, attached by Scotch tape to one end of cigarettes to prepare samples for measuring the pressure drop and the amount of phenols in tobacco smoke and for organoleptic test.

On the other hand, a control filter was prepared under the same conditions as above, except that the aqueous emulsion was not sprayed to the paper.

The filter of the present example and the control filter were compared in pressure drop and in amount of phenols in tobacco smoke passed through the filter to obtain the results as set forth in table 8.

TABLE 8

Kind of filter	Pressure drop (mm. H ₂ O)	Phenols in smoke (mg./cigarette)
Control filter	50	0.061
Filter of Example 8	49	0.057

As is clear from the above examples, a tobacco smoke filter made of the filter-forming material containing the ester ether compounds of saccharides is excellent in ability for removing the harmful substances present in tobacco smoke due to the nonionic surface activities of the compounds. And the compounds are easily penetrated to the filter-forming material.

What is claimed is:

1. A tobacco smoke filter conforming to the smoke passageway of a tobacco smoking article, said filter comprising a filter-forming material containing 0.01 to 30 percent by weight of at least one member selected from the group consisting of compounds represented by the general formulas

70

wherein R₁, R₂, R₃, R₄, R₅, R₆, R₇, and R₈ represent one member selected from the group consisting of (1) a polyalkylene glycol ether group selected from the group consisting of polyethylene glycol ether group, polypropylene glycol ether group, polyethylenepropylene glycol ether group and polybutylene glycol ether group (2) a fatty acid ester group and (3) hydrogen, one of R₁ to R₈ being said polyalkylene glycol ether group and at least one of the remainder of R₁ to R₈ being a fatty acid ester group.

2. A tobacco smoke filter according to claim 1 wherein one to two of R₁ to R₈ is a fatty acid ester group and has two to 19 carbon atoms.

3. A tobacco smoke filter according to claim 2 wherein the chain length of the polyalkylene glycol residue is 1 to 50 moles.

4. A tobacco smoke filter according to claim 3 wherein the compound is a sucrose or glucose derivative.

5. A tobacco smoke filter according to claim 4 wherein the polyalkylene glycol group has eight to 10 glycol units and the fatty acid ester group has two to 15 carbon atoms.

6. A tobacco smoke filter according to claim 1, wherein said filter-forming material is crimped cellulose acetate fibers.

7. A tobacco smoke filter according to claim 1 wherein said filter-forming material is polyolefin fibers.

8. A tobacco smoke filter according to claim 1 wherein said filter-forming material is cellulose fibers.

9. A tobacco smoke filter according to claim 1 wherein said filter-forming material is cellulose paper.

10. A tobacco smoke filter according to claim 1 wherein said filter-forming material is polyvinyl alcohol sponge.

11. A tobacco smoke filter according to claim 1 wherein said filter-forming material is a member selected from the group consisting of polystyrene sponge and polyvinyl acetate sponge.

12. A tobacco smoke filter according to claim 1 wherein said filter-forming material is cellulose acetate sponge.

13. A tobacco smoke filter according to claim 1 wherein said filter forming material is crimped fibers having a single fiber denier of 1 to 10 and a total denier of 20,000 to 100,000.

14. A tobacco smoke filter according to claim 2, wherein said crimped cellulose acetate fibers have a single fiber denier of 1 to 10 and a total fiber denier of 20,000 to 100,000.
